H. SILVER

TABLE PAD

Filed Oct. 1, 1921

Henry Silver, Inventor
By Frank S. Amerman

Attorney

UNITED STATES PATENT OFFICE.

HENRY SILVER, OF HERKIMER, NEW YORK.

TABLE PAD.

Application filed October 1, 1921. Serial No. 504,658.

To all whom it may concern:

Be it known that I, HENRY SILVER, a citizen of the Province of Poland, Russia, and resident of Herkimer, in the county of Herkimer and State of New York, have invented 5 certain new and useful Improvements in Table Pads, of which the following is a specification.

This invention relates to table pads, and 10 particularly to a device intended to prevent when used the marking of the finish of articles of furniture incident to the weight of articles which may rest on the furniture, especially where the articles are heavy, such 15 table pad being designated by me as "a furniture finish protector."

It is well known that even though the ordinary pads are employed between lamps, ornaments and the like and the surface of an 20 article of furniture on which they rest, the pressure or weight of the article compresses the pad to such an extent as to cause the varnish of the furniture to become impaired or marked, and if a pad is not interposed between 25 the furniture and the article, the furniture becomes scratched and defaced.

It is an object of this invention, therefore, 30 to produce a pad having the desirable quality of neutralizing shock and weight of the character indicated, to such an extent as to render it unlikely that the pad will become so distorted as to localize the weight supporting portions of the pad. In the pad of the invention where the weight is somewhat 35 localized at the top where the article rests on it, the weight is distributed, to a great extent, by the filler of the pad, and this, in connection with a coating of novel character, maintains the varnish or finish of the table 40 or other article of furniture in a state which precludes its being injured, to the extent that it is injured, under ordinary conditions of use.

It is a further object of this invention to 45 produce a pad of the character indicated which may be made ornamental, useful and which will prove comparatively inexpensive to manufacture, the article when not used as a table pad being capable of use to wax 50 the surface of furniture by rubbing the under side of the pad upon the surface, after which such surface with the wax applied thereto may be polished.

With the foregoing and other objects in 55 view, the invention consists in the details of

construction, and in the arrangement and combination of parts to be hereinafter more fully set forth and claimed.

The accompanying drawing illustrates the invention by a perspective view, partly in 60 section.

Referring to the drawing, 1 indicates a rigid fibrous body such as paper board of appropriate thickness having the usual smooth surfaces, the inner portion being less 65 dense than its upper and lower surfaces, the fibrous interior being absorbent. The body portion is cut to suitable size and shape for use as a table pad, the finished article being adapted for use not only as a table pad, but 70 also as a pad for shop and show window use upon which to place and display merchandise.

The rigid body 1 of fibrous material when 75 cut to shape is boiled in paraffin wax for a length of time sufficient to impregnate it with the liquefied wax, and after such treatment the body has applied thereto a comparatively thick surface covering 2 of the same material. The surface covering is removed from one side in any suitable manner, as by scraping, thus leaving on one side of the body 1 and the margin thereof a covering of wax. The upper side then has applied thereto a dense coating or film of glue, or other adhesive material 3, which is utilized to hold in place a covering 4 of such character as to provide an ornamental upper surface, as is commonly used upon table mats. The coating 3 serves to prevent the paraffin wax being drawn through the covering 4, as in use the wax is liable to be drawn by convection when a heated dish or object rests upon the mat.

I prefer to use a solidified paraffin wax 9 for the reason that it is translucent. It is also a suitable material for polishing the surface of furniture when applied thereto and rubbed. Paraffin wax when applied as a base to a piece of fibre-board renders the 100 same practically noiseless, and not being brittle, will not scratch the surface to which it is applied. Further, paraffin wax, when rubbed upon the finished surface on which the pad is placed, will obliterate, or render 105 less apparent, scratches or defacement of the previously polished surface. Furthermore, this wax is translucent and this property is utilized by me because it will not obscure the coloring, texture or any printed matter, 110

for instance, a trade mark and directions for use, that may be applied to the under surface of the table mat.

5 Before the application of the wax to the body or base 1 of the pad, I may attach or impress to what will be the under side of the body 1 in use, a label or printed impression of a trade mark and directions for use, or other printed matter.

10 I claim:

1. As an improved article of manufacture, a table mat or pad comprising a rigid body of fibrous material impregnated and coated

on one side only with paraffin wax, the opposite side having thereon a coating of adhesive material. 15

2. As an improved article of manufacture, a pad consisting of a rigid body made up of fibrous paper stock which is impregnated with paraffin wax, a coating of like material 20 intimately connected to one face only of the rigid body portion, said pad or mat having on the opposite side a coating of adhesive material in film-like form, and a covering held in place by said adhesive.

HENRY SILVER.
